[57] **CLAIM**

The ornamental design for a faucet with an extendable water outlet, as shown and described.

DESCRIPTION

FIG. 1 is a side perspective view of a faucet with an extendable water outlet, showing my new design the tubes being shown in fragmented condition;

FIG. 2 is a top plan view thereof;

FIG. 3 is a side elevation view thereof;

FIG. 4 is a front elevation view thereof;

FIG. 5 is a rear elevation view thereof;

FIG. 6 is an opposite side elevation view thereof;

FIG. 7 is a bottom plan view thereof, with the conduits removed;

FIG. 8 is a side elevation view of a faucet with an extendable water outlet with the conduits shown; and.

FIG. 9 is a side elevation view of a faucet with an extendable water outlet, whereby the water outlet is partially extended. The conduits are shown broken away in FIGS. 1, and 3-6 for ease of illustration.
